Charles H. Brand, of Philadelphia, Penna.

Assignor to

Harrison Brothers & Coo of the same place

Letters Patent No 1995 Dated Nov 8th 1864.

Design for a Paint Can.

The schedule referred to in these Letters Patent and, making part of the same.

To all whom it may concern:

Be it known that I, Charles H. Brand, of the City, County of Philadelphia, and State of Pennsylvania, have invented or produced a new and original design for Paint Cans, and I do hereby declare that the following is a full and exact description of the same, reference being had to the annexed drawings, making a part of this specification, in which

Figure 1, is a perspective view of the can.

Figure 2, is a vertical section of the same.

Figure 3, is a face view of the bottom of the can.

Figure 4, is a perspective view of one of the ears. The

like letters in all the figures represent the same parts.

The nature of my invention or production will be understood by the following description.

I stamp the letter H on the bottom B, of the can, and within the patent mark as represented in figure 3, the said letter representing the firm of my associates.
